UNITED STATES PATENT OFFICE.

FREDERICK C. SEBULSKY, JR., OF DETROIT, MICHIGAN.

DESIGN FOR A WASHING-MACHINE CASING.

Application filed September 13, 1926. Serial No. 19,041. Term of patent 14 years.

To all whom it may concern:

Be it known that I, FREDERICK C. SEBULSKY, Jr., a citizen of the United States, residing at Detroit, in the county of Wayne and State of Michigan, have invented a new, original, and ornamental Design for Washing-Machine Casing, of which the following is a specification, reference being had to

the accompanying drawing, forming part thereof.

The figure is an elevation of a washing machine casing showing my new design.

I claim:

The ornamental design for a washing machine casing as shown.

FREDERICK C. SEBULSKY, JR.
